UNITED STATES PATENT OFFICE.

EDWARD F. BACHELLER, OF LYNN, MASSACHUSETTS, ASSIGNOR OF ONE-HALF TO JOHN HAMMOND STEWART, OF LYNNFIELD, MASSACHUSETTS.

DESIGN FOR A GOLF-PUTTER HEAD.

58,209.

Specification for Design.

Patented June 28, 1921.

Application filed February 10, 1921. Serial No. 444,043. Term of patent 14 years.

To all whom it may concern:

Be it known that I, EDWARD F. BACHELLER, a citizen of the United States, residing at Lynn, in the county of Essex and Commonwealth of Massachusetts, have invented a new, original, and ornamental Design for a Golf-Putter Head, of which the following is a specification, reference being had to the accompanying drawing, forming part thereof.

I claim:

The ornamental design for a golf putter head as shown.

EDWARD F. BACHELLER.
